CONTAINER CLOSURE

August Mitchell, New York, N. Y., assignor to
 American Tube and Cap Corporation, Jersey
 City, N. J., a corporation of Delaware

Application August 4, 1933, Serial No. 683,567

5 Claims. (Cl. 221—60)

This invention relates to closure devices, and is in the nature of a specific improvement in closure means of the type disclosed in the Reissue Patent No. 18,649, to Walther Kalb, issued November 8, 1932.

My invention is directed primarily to simplicity of construction, ease of assembly, and to the provision of a closure device which can be applied with expedition and facility to containers of known construction and which are now in common use. Further objects and advantages of my invention will appear from the detail description.

In the drawing:—

Figure 1 is a plan view of a closure device embodying my invention, as applied to a container in the form of a tube such as is commonly used for containing tooth paste and other materials;

Figure 2 is a vertical sectional view through the closure device of my invention, taken substantially on line 2—2 of Figure 1, the tube being shown as partly broken away and in section;

Figure 3 is a view similar to Figure 1, but with the cap of the closure device omitted; and

Figure 4 is a view similar to Figure 2, but showing a modified form of closure device in accordance with my invention.

The closure device of my invention comprises a tubular neck 1 of cylindrical form, the lower portion 1a of which is reduced to provide an outwardly projecting shoulder 2 extending around the neck circumferentially thereof. Neck 1 is provided, at its upper end, with a cover 3 from the central portion of which projects a cylindrical boss 4. The cover is provided with arcuate slots or openings 5 disposed outwardly beyond boss 4 and concentrically therewith, these openings extending through a downwardly and outwardly inclined shoulder 6 of the cover connecting the upper end of the neck and the base of boss 4.

40 A snap member 7 fits snugly about neck 1 beneath shoulder 2 thereof. This member may be formed of any suitable resilient material, such as spring brass, is annular in plan and of channel cross-section. Inner flange 8 of member 7 provides a short collar which fits snugly about the neck beneath shoulder 2, as shown in Figure 2. The snap member is dished or distorted so that, when this member is flexed in either direction beyond its mid or neutral position, it moves beyond this position and in such direction with a snap action.

45 A closure cap 9, which is preferably solid and may be formed of a condensation product, such as the product known commercially as "bakelite", is mounted in the snap member 7. Cap 9 is conveniently of the shape of a segment of a sphere and is attached, at its outer portion, to member 7 by beading the upper edge portion of outer flange 10 of member 7 over the outer edge portion of the cap, as at 10a. The under face of cap

9 is preferably slightly concaved to provide clearance 11 between the cap and member 7 to facilitate flexing of the latter.

The cap is provided with a suitable bore extending from its under face and of proper diameter to receive snugly neck 1 so that the cap is slideable upon and guided by the neck. The cap is further provided, at the upper end of this bore, with an inwardly projecting and tapering flange 12 shaped to fit snugly about boss 4 and seat snugly upon shoulder 6 of the cover 3 so as to close the openings 5. When in closed position, the cap thus provides a tight closure about boss 4 as well as a tight closure for the openings 5, this double closure eliminating possibility of access of air to the contents of the associated container and consequent drying thereof. The snug fit of cap 9 about neck 1 is also of assistance in preventing access of air to the openings 5 when the cap is in closed position.

5 The closure device provides a unit which may be applied with expedition and facility to a container of ordinary type, such as a collapsible tube T of a type commonly used for containing tooth paste and various other materials. This tube is provided, at its upper end, with a short collar c. The lower portion 1a of neck 1 of proper diameter to fit snugly through collar c of the tube T, and the lower end of the tube is left open until the proper quantity of the desired material has been placed within the tube, in accordance with present practice, after which the lower end of the tube is closed and sealed in a known manner. Neck 1 of the closure device is preferably formed of a relatively soft and ductile metal, such as 10 flock tin. In applying the closure device to the tube, lower portion 1a of the neck 1 is inserted through collar c until the lower edge of flange 8 of member 7 seats tightly against the upper edge of the collar, at which time the lower end portion of neck 1 occupies the dotted line position of Figure 2. This portion of neck 1 is then expanded radially, in a suitable manner, so as to engage beneath shoulder d of the tube T extending between the body of the tube and collar c, as shown in full lines in Figure 2. During the operation of expanding the lower end of neck 1, the collar c and adjacent portion of the tube may be supported in a suitable form, as is known in the art, to prevent deforming of the tube. After the 15 lower end of neck 1 has been spread in this manner, the closure device is effectively anchored to the tube, the contents of which may be discharged through neck 1 and openings 5. Cap 9 is normally held in closed position by snap member 7, which urges the cap toward cover 3 of neck 1 and holds it firmly seated. When it is desired to 20 discharge the contents of tube T, the outer edge portion of member 7 is grasped and this member 25 and the cap are moved away from cover 3. As 30

35 neck 1 is spread, the closure device is effectively anchored to the tube, the contents of which may be discharged through neck 1 and openings 5. Cap 9 is normally held in closed position by snap member 7, which urges the cap toward cover 3 of neck 1 and holds it firmly seated. When it is desired to 40 discharge the contents of tube T, the outer edge portion of member 7 is grasped and this member 45 and the cap are moved away from cover 3. As 50 neck 1 is spread, the closure device is effectively anchored to the tube, the contents of which may be discharged through neck 1 and openings 5. Cap 9 is normally held in closed position by snap member 7, which urges the cap toward cover 3 of neck 1 and holds it firmly seated. When it is desired to 55 discharge the contents of tube T, the outer edge portion of member 7 is grasped and this member 60 and the cap are moved away from cover 3. As

soon as the cap 9 moves outwardly across the mid or neutral position of member 7, this member acts with a snap action to move the cap into its full open position indicated by dotted lines in Figure 5 2, in which position the cap is retained by the snap member. After the desired amount of material has been discharged from the tube T, through the openings 5 and the opening defined by flange 12 of the cap, the cap is pushed toward 10 the tube until snap member 7 passes its mid or neutral position, after which member 7 completes closing of the cap with a snap action and thereafter urges the cap in closing direction so as to maintain the closure of openings 5 and prevent 15 access of air to the tube. Any slight amount of tooth paste or other material contained within the tube T, which may be expelled between flange 12 and boss 4 incident to closing of the cap, may be wiped from the upper end of boss 4 and adjacent 20 portions of the cap, assuring that no material remains which, on drying, due to contact with the air, might interfere with opening of the cap.

While I have illustrated the closure device of 25 my invention as applied to a collapsible tube of known type, such as is commonly used for containing tooth paste and various other materials, it will be understood that this device is capable of being used with various types of other containers such as are now in common use.

In Figure 4 I have illustrated a modified form 30 of my invention. This form is similar to that illustrated in Figures 1 to 3, inclusive, with the exception that the snap member 7a is provided 35 with a plurality of concentric corrugations 7b. These corrugations are advantageous in certain instances as facilitating flexing of the snap member. Otherwise, the construction and operation of the form of device illustrated in Figure 4 are 40 similar to the construction and operation of the device illustrated in Figures 1 to 3, inclusive, and need not be further described.

What I claim is:—

1. In combination in a closure device of the 45 character described, a tubular neck having at one end a cover provided with openings therethrough, said neck being provided with an outer circumferential shoulder remote from its other end, the portion of the neck between said shoulder and said other end of the neck being adapted for insertion into a corresponding tubular element of an associated container, a cap having a discharge opening and movable lengthwise of the neck and adapted to seat on said cover and close the 50 openings thereof, and a snap member fitting about the neck beneath the shoulder thereof and attached at its outer edge to the cap, the inner edge of the snap member being disposed to be confined between said shoulder and said tubular 55 element when the closure device is applied to said container, said member acting to move the cap from and toward the cover by a snap action, when the cap is moved beyond neutral position, and to hold the cap seated on the cover.

60 2. In combination in a closure device of the character described, a tubular neck having at one end a cover provided with an outwardly projecting boss and with openings adjacent the inner end of the boss, said neck being provided with 65 an outwardly extending shoulder thereabout, a cap slidably mounted upon the neck and provided with a flange of a size and shape to fit snugly

about the boss and seat upon the cover and close the openings thereof, and a resilient snap member fitting about the neck beneath the shoulder and attached to the cap, said member acting to move the cap away from and toward the cover when the cap is moved beyond neutral position, and to hold the cap seated upon the cover, the cap being guided by the neck in the movement of said cap from either of its extreme positions into its other extreme position, the portion of the 10 neck between the other end thereof and said shoulder being adapted for insertion into a tubular element of a container.

3. In a closure device of the character described, a tubular neck formed of relatively soft 15 and ductile metal and having at one end a cover provided with openings therethrough, said neck being provided with an outwardly projecting shoulder extending thereabout, a cap having a discharge opening and movable lengthwise of the 20 neck and adapted to seat upon the cover and close the openings thereof, and a snap member connecting the cap and the neck and fitting about the latter beneath the shoulder, said member acting to move the cap toward and away from 25 the cover when the cap is moved beyond neutral position, and to hold the cap seated upon the cover, the snap member having a collar of considerable width at its inner edge fitting snugly about the neck beneath said shoulder, and the 30 portion of the neck between the other end thereof and said collar being adapted for insertion into a corresponding tubular element of a container.

4. In a closure device of the character described, a tubular neck having at one end a cover provided with an outwardly projecting boss and with openings located between the inner end of the boss and the outer periphery of the neck, said neck being provided below the cover with an 40 outwardly extending shoulder thereabout, a snap member substantially annular in plan and of channel cross-section fitting about the neck beneath said shoulder, and a solid cap fitting snugly about and slidably on the neck and mounted in 45 said member with its outer portion attached thereto, said cap being provided with a flange of a size and shape to fit snugly about the boss and seat upon the cover and close the openings thereof, said snap member acting to urge the cap toward and away from the cover when the cap is moved beyond neutral position, and to hold the 50 cap seated upon the cover.

5. In a closure device of the character described, a tubular neck having at its upper end a 55 cover provided with an outlet opening, a cap having a discharge opening movable lengthwise of the neck and adapted to seat upon the cover and close the opening thereof, the lower portion of the neck being of reduced diameter to provide 60 an outwardly projecting shoulder thereabove, and a snap member fitting about the neck and held by said shoulder against movement lengthwise thereof toward said cover, said member connecting the cap and the neck and acting to 65 move the cap toward and away from the cover by a snap action, when the cap is moved beyond neutral position, the lower reduced portion of the neck being adapted for insertion into a corresponding tubular element of a container.

AUGUST MITCHELL.
